(57) CLAIM

The ornamental design for a display screen with a graphical user interface for dental software, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view of a display screen with a graphical user interface for dental software showing my design.

FIG. 2 is a front view of the design of FIG. 1, shown in an alternative unclaimed environment.

FIG. 3 is another front view of the design of FIG. 1, shown in an alternative unclaimed environment.

FIG. 4 is another front view of the design of FIG. 1, shown in an alternative unclaimed environment.

FIG. 5 is another front view of the design of FIG. 1, shown in an alternative unclaimed environment.

FIG. 6 is another front view of the design of FIG. 1, shown in an alternative unclaimed environment.

FIG. 7 is another front view of the design of FIG. 1, shown in an alternative unclaimed environment.

FIG. 8 is another front view of the design of FIG. 1, shown in an alternative unclaimed environment.

FIG. 9 is another front view of the design of FIG. 1, shown in an alternative unclaimed environment.

FIG. 10 is another front view of the design of FIG. 1, shown in an alternative unclaimed environment; and,

FIG. 11 is another front view of the design of FIG. 1, shown in an alternative unclaimed environment.

The broken lines in the drawings illustrate the environment of the claimed design and form no part thereof.

1 Claim, 11 Drawing Sheets
